UNITED STATES PATENT OFFICE

WILLIAM SHEPPARD WALLACE, OF CHARLOTTE, NORTH CAROLINA

TABLETING PRESS

Application filed May 23, 1929. Serial No. 365,551.

The object of my invention is to provide a novel and more efficient tableting press for the use of printing offices in holding paper together until it can be glued in pads, and 5 then holding the pads under pressure while the glue is applied and during the period required for the glue to dry.

It is an especial object of my invention to provide a device which will permit of gluing 10 a large quantity of sheets at one time and which will maintain an even pressure on all parts of the pads.

It is also an object of my invention to provide a novel type of spring, especially 15 designed for use as a part of my tableting press. It is also an object of my invention to provide a device which is adjustable for use with different size sheets; and to provide the novel combination and arrangement of 20 parts disclosed in the accompanying drawings, and described in the following specification.

I attain these and other objects of my invention by the device shown in the accompanying illustrations, in which,—

Figure 1 is a side elevation of my invention in use;

Fig. 2 is a front plan view of same;

Fig. 3 is a perspective view of the spaced 30 pressure blocks;

Fig. 4 is a longitudinal section through one of the blocks;

Fig. 5 is a detailed view of one of the 35 springs, portions of which are diagrammatically shown;

Fig. 6 is a perspective view of different size pads which can be held and glued conveniently in my device;

Fig. 7 is a side elevation of a modified and 40 preferred form of my invention; Fig. 8 is a face view of the bar 29 with the spring section 15 attached; and

Fig. 9 is a side elevation of same.

Like characters of reference designate like 45 parts in each of the several views.

Referring to the accompanying drawings, I provide a wooden or other suitable base 5, to which is attached a triangular metal bracket 10, which functions to support the 50 trough 7, which trough is provided with

suitable side strips 8 to guide the pads of paper P. In the lower end of the trough 7 is a rigid end strip 9, disposed at right angles to member 7.

I provide a pair of blocks, one of which is 55 designated 11 and the other 12, to hold the pads in place on the trough. Each of the blocks 11 and 12 is provided with a plurality of openings 22 and 24, arranged as shown in Figs. 3 and 4 of the drawings. I also provide three parallel grooves 19 in the outer surface of each of the blocks 11 and 12, in which grooves are mounted the hooks 20, 25, and 26 on one of the blocks; and the hooks 21, 27 and 28 on the other block. 60 Hooks 20 and 21 project over the ends of the blocks; hooks 25 and 27 project into the openings 22; and hooks 26 and 28 project into the openings 24, as shown in Fig. 3.

I provide a novel type of spring comprising 65 the spiral sections 15, 16 and 17, with loops 18 intervening between these sections and disposed at substantially right angles to the plane of the spirals in the sections; the springs also having similar loops 18 at their 70 ends. Any one of the loops 18 may be hooked in the hooks 20 and 21.

I provide a suitable hinge 6, having one of its arms affixed to the trough 7, and having the other arm affixed to the base 5; the 75 hinge being disposed in proximity to the triangular bracket 10.

In operation the trough may be disposed 80 in the position shown in Fig. 1, resting against the triangular bracket 10, while the sheets are being stacked on the trough. When the sheets to make up the pads have been 85 assembled, and the springs adjusted and fastened to the respective blocks 11 and 12, to place the sheets under pressure, the trough 90 is turned to an upright position, thereby giving the operator easy access to the stack and enabling him to remove same with little 95 trouble after the glue has been applied and allowed to dry, so as to place other stacks in the trough.

The device gives more even pressure on the stack of paper than the old fashioned press. Four of the springs are used, two on each side and the loops arranged at spaced intervals 100

between the sections of the springs permit of hooking the springs for any desired length to the respective end blocks 11 and 12, thus providing a convenient method of adjusting the springs to exert the required pressure on the paper to be glued. The blocks 11 and 12 are preferably pressed out of one sheet of metal, with the retaining hooks made a part of the blocks, but they may be separate elements as illustrated in the drawings, if preferred.

The inside of the metal blocks are covered with cork or felt to keep them from damaging or spoiling the paper against which they are placed.

Under the old process now in general use, a printer has to buy a separate pair of boards for each size of paper he desires to pad, while my invention is adjustable so that any width of sheets from 11 inches to 3 inches or less, such as the pads A, B and C, shown in Fig. 6, may be held in the device and glued together.

I may provide a modification of my invention in which instead of the novel type of spring shown I utilize an ordinary coil spring 15 in any suitable manner affixed as at 31 to a strip of metal 29, this strip of metal 29 having several spaced holes 30 in it which holes function in a similar manner and in place of the elements 18 of the coil spring shown in Figs. 1 and 2. This construction may be utilized in place of the coil springs because of being cheaper to manufacture. The term, "coil springs," as used in the following claims shall be construed to include an equivalent resilient device comprising a coil spring affixed to a strip of metal and functioning in approximately the same manner as the device illustrated.

What I claim is:

1. A tabletting press, comprising a trough, a base, hinged means for mounting the trough on the base, a bracket for supporting the trough in a slanting position, said trough having a rigid end member at the lower end for supporting the contents of the trough, a pair of blocks, each of said blocks having a plurality of hooks projecting from opposite ends of same, and a series of coil-springs having a plurality of loops disposed substantially at right angles to the planes of the coils of the springs, whereby any of the loops may be engaged in the hooks of the blocks to adjustably exert pressure on pads or sheets mounted between the respective blocks.

2. A tabletting press, comprising a trough, a base, hinged means for mounting the trough on the base, a bracket for supporting the trough in a slanting position, said trough having a rigid end member at the lower end for supporting the contents of the trough, a pair of blocks, each of said blocks having a plurality of hooks projecting from opposite ends of same, and a series of coil-springs hav-

ing a plurality of loops disposed substantially at right angles to the planes of the coils of the springs, whereby any of the loops may be engaged in the hooks of the blocks to adjustably exert pressure on pads or sheets mounted between the respective blocks, the blocks also having spaced apertures and hooks projecting from the blocks and the said hooks being engaged by the aforesaid springs for operating on sheets of paper of smaller size than the blocks.

3. A tabletting press, comprising a trough, a base, hinged means for mounting the trough on the base, a bracket for supporting the trough in a slanting position, said trough having a rigid end member at the lower end for supporting the contents of the trough, a pair of blocks, each of said blocks having a plurality of hooks projecting from opposite ends of same, and a series of coil-springs having a plurality of loops disposed substantially at right angles to the planes of the coils of the springs, whereby any of the loops may be engaged in the hooks of the blocks to adjustably exert pressure on pads or sheets mounted between the respective blocks, the blocks having a plurality of rows of spaced apertures, said hooks being engaged by the aforesaid springs for operating on sheets of paper of smaller size than the blocks.
